US0D1017363S

(12) **United States Design Patent** (10) **Patent No.:** **US D1,017,363 S**
(45) **Date of Patent:** **** Mar. 12, 2024**

(54) **BUFFING PAD**

(71) Applicant: **Jiangzhao Liu**, Yichang (CN)

(72) Inventor: **Jiangzhao Liu**, Yichang (CN)

(73) Assignee: **Jiangzhao Liu**, Yichang (CN)

(**) Term: **15 Years**

(21) Appl. No.: **29/912,949**

(22) Filed: **Sep. 26, 2023**

(51) **LOC (14) Cl.** **08-05**

(52) **U.S. Cl.**

USPC **D8/70**; D32/40

(58) **Field of Classification Search**

USPC D8/70; D32/40

CPC B24D 13/12; A46B 2200/3046

See application file for complete search history.
